Primary Examiner — Tracey J Bell

(57) **CLAIM**

I claim the ornamental design for a gemstone, as shown and described.

DESCRIPTION

FIG. 1 is a top plan view of a gemstone showing my new design;

FIG. 2 is a front elevation view, with the rear view, left side view and right side view being a minor image thereof; and, FIG. 3 is a bottom plan view thereof.

1 Claim, 3 Drawing Sheets**FIG. 1**

FIG. 2

FIG. 3
